(74) *Attorney, Agent, or Firm* — Michael Best & Friedrich LLP

(57) **CLAIM**

I claim the ornamental design for a horizontal trifold cell phone wallet, as shown and described.

DESCRIPTION

FIG. 1 is a perspective view of a horizontal trifold cell phone wallet showing the new design in a closed condition;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective view of the horizontal trifold cell phone wallet in an open condition;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof.

FIG. 15 is a perspective view of the horizontal trifold cell phone wallet in a stand configuration;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The present application is directed to the design illustrated in the drawings. Portions shown in broken lines form no part of the claimed design.

1 Claim, 16 Drawing Sheets

Related U.S. Application Data

a continuation of application No. 29/524,368, filed on Apr. 20, 2015, now Pat. No. Des. 756,643, which is a continuation of application No. 29/449,461, filed on Mar. 15, 2013, now Pat. No. Des. 730,646.
